CLAIM

The ornamental design for an atomizer, as shown and described.

DESCRIPTION

FIG. 1 is a perspective view of the claimed design.

FIG. 2 is a front view of FIG. 1;

FIG. 3 is a rear view of FIG. 1;

FIG. 4 is a left view of FIG. 1;

FIG. 5 is a right view of FIG. 1;

FIG. 6 is a top view of FIG. 1; and,

FIG. 7 is a bottom view FIG. 1.

The broken lines shown in the figures are for the purpose of illustrating portions of the atomizer and form no part of the claimed design.
